W. P. PARROTT.
Railroad-Car Truck.

No. 79,252.

Patented June 23, 1868.

United States Patent Office.

WILLIAM P. PARROTT, OF BOSTON, MASSACHUSETTS, ASSIGNOR TO N. F. BRYANT, OF SAME PLACE.

Letters Patent No. 79,252, dated June 23, 1868.

IMPROVEMENT IN RAILWAY-TRUCKS.

The Schedule referred to in these Letters Patent and making part of the same.

TO ALL WHOM IT MAY CONCERN:

Be it known that I, WILLIAM P. PARROTT, of Boston, in the county of Suffolk, and Commonwealth of Massachusetts, have invented certain new and useful Improvements in Railway-Car Trucks; and I do hereby declare that the following, taken in connection with the drawings which accompany and form part of this specification, is a description of my invention sufficient to enable those skilled in the art to practise it.

My invention relates to the adaptation of railway-cars to run upon tracks of different gauges, the invention having for its object the lateral separation and drawing in of the opposite wheels upon and by the track-rails, so that the car can be run from track to track by any ordinary motive-power.

Until of late years, it has been customary, in the laying and building of railways, to observe a fixed and regulated width between the rails, so that railways making connection with each other always had uniform tracks, and the cars running upon one could be used upon the other, and a car, wherever built, had this fixed width between the wheels, adapting it to any and all the railway-tracks of the country. More recently, however, railways have been constructed of wider gauge, and where wide and narrow gauges connect, freight and passengers have had to be transferred from the cars of one road to those of the other, as, unless the cars were built with wheels made capable of lateral movement with respect to each other, or to draw from or away from each other, to regulate their distance apart to the different tracks, employment of the same cars upon both was impossible.

To a very limited extent, cars have been constructed before my invention with wheels capable of such lateral movement, such wheels sliding upon their axles; but in order to transfer them from track to track, it was necessary to raise the car-body and wheels above and free from the track, when the wheels were moved in the requisite directions, and the car then lowered upon the other track. By my invention, this operation of moving the wheels is effected upon and by the track-rails, so that the car does not have to be displaced from or raised above the track, but runs from one track to the other without impediment. In the drawings—

Figure 1 denotes a top view of two railway-tracks and a car-truck.

Figure 2 is a longitudinal section of the car-truck.

Figures 3 and 4 are cross-sections of the truck taken through one of the car-axles, and showing the position of the wheels upon both wide and narrow tracks.

A A' denote the rails of the wide track, and B B' those of the narrow track.

a is the frame of the car-truck, b b' c c' the wheels thereof, and d d' the axles. Each axle is shown as made in two parts, the wheels being confined in the usual manner upon the axles, and the part e of each axle being capable of sliding within a sleeve or tube, f, in the other part, so that they do not rotate independently, but as one axle, a spline or pin and groove keeping them from independent rotation, but allowing the wheels to separate or move towards each other.

When the car is upon the narrow track, the wheels are confined in position by a pin, g, inserted in the axle, as seen in fig. 3, and when upon the wide track, by inserting the pin in other holes in the axle, as will be readily understood.

Between the opposite rails of each track, A A' and B B', are two inclined rails, C C', which constitute a connecting or wheel-changing track, and parallel to each rail, C C', is a guide and wheel-changing rail, D D', and between these adjacent rails the car-wheels run from track to track, the wheels being drawn together or apart as the car may be passing from track A A' to track B B', or vice versa.

Suppose the car is in the position seen in fig. 1, and is to be transferred to the track B B', the pin connecting the two parts of the axle being withdrawn, as the car advances the flanges of the wheels abut against the inner side of the rails C C', which causes the wheels to move towards each other until they reach the parallel rails B B', when the confining-pin is again inserted in the axle. If running from the track B B' to the track A A', the wheels abut against the outer edges of the guard-rails D D', and are separated until they reach the parallel rails A A'.

I do not intend to confine my invention to the exact method shown of applying the car-wheels and axles to the car-trucks, as wheels sliding upon axles, or otherwise made capable of proper lateral movement, may be employed.

I claim the combination and arrangement of a car-truck with laterally-moving wheels, as described.

WM. P. PARROTT.
